UNITED STATES PATENT OFFICE.

FOUNTAIN LIVET, OF LONDON, COUNTY OF MIDDLESEX, ENGLAND.

STEAM-GENERATOR.

SPECIFICATION forming part of Letters Patent No. 295,775, dated March 25, 1884.

Application filed October 13, 1883. (No model.) Patented in England August 18, 1883, No. 4,007.

To all whom it may concern:

Be it known that I, FOUNTAIN LIVET, a subject of the Queen of Great Britain and Ireland, of Short Street, Finsbury Pavement, London, 5 in the county of Middlesex, England, have invented certain Improvements in Internally-Fired High-Pressure Steam-Generators, and in the setting of the same, (for which provisional protection has been granted to me by the 10 government of Great Britain, No. 4,007, dated August 18, 1883,) of which the following is a specification.

This invention relates to certain improvements in the construction of internally-fired 15 high-pressure steam-generators, as described in the Letters Patent granted to me November 6, 1883, No. 288,079.

My invention consists in a novel construction and combination of parts, whereby economy is secured by obtaining a maximum available heating-surface with a minimum fuel consumption, combined with greater facility for cleaning and inspection and a minimum contact of brick-work with the boiler.

25 Figure 1 is a sectional plan view through the flues about the two lower cylinders. Fig. 2 is a sectional plan through the flues around the upper cylinder. Fig. 3 is a vertical longitudinal section. Fig. 4 is a transverse vertical section 30 through the cylinders and connecting-tubes, and Fig. 5 is a sectional view through the upper cylinder and flues at the ends of the two lower cylinders.

I will now proceed with a description of my 35 improvements, aided by the drawings attached.

The boiler is of a compound nature, and consists of two lower cylindrical tubes, A and B, made preferably not more than five feet in diameter, having flat ends and one furnace-tube 40 in each. A and B are connected by several conical tubes, D, to one upper cylinder, E, which may be from five to six feet in diameter. The crown of each furnace-tube C slopes up from, say, the second expansion-ring to a point 45 over the back end of the bridge, rising some four or five inches in all, as shown, at F, Fig. 3, and in the expanded portion of the furnace-tubes conical or other cross tubes may be placed

in the ordinary way. The upper cylinder, E, is connected by conical tubes D to the lower cylinders, A and B. These tubes are about double the area at the top H, where connected to the upper cylinder, than that at the lower end, J, connected with the lower cylinders, A and B, the weight of the upper cylinder being 50 entirely supported by the connecting-tubes D. The water-level is maintained a little above the half of the diameter of the upper cylinder, E, the space between such water-level and the top 55 of the cylinder serving as a steam-chest, and the whole boiler is supported on any convenient number of cast-iron saddles, K, under the lower cylinders, A and B.

In describing the course of the flues I will follow the current from one of the lower cylindrical tubes, both flues being the same. The current is on the wheel-draft principle. The gases pass through the furnace-tube C into an expansion-chamber, L, having a deep pit or receptacle below the level of the side flues for 60 the reception of grit. They then pass into a side flue, N, the top of which is carried up to the apex O of the lower cylinder, and the bottom of which is of inverted-arch form P. The sectional area of this first flue, N, is larger than 65 that of the furnace-tube C, and it is placed on the outside of the boiler farthest away from the center. The gases then pass into another expansion-chamber at Q, the sectional area of 70 which is greater than that of the first flue N, and they then emerge into the second side flue, 75 R, the area of which is greater than the sectional area of the second expansion-chamber, Q. The gases from both lower cylinders, A and B, then pass into the end chamber, S, and 80 rise up under the end of the upper cylinder into a side flue, T, of larger sectional area than both the second return-flues, R, of the lower cylinders, and continue across under the front 85 of the upper cylinder into another flue, U, larger than the last-named side flue, T. Thus 90 the gases pass in one continuous flue five times the length of the boiler before going through the damper-flue Z into the chimney.

The divisions between each pair of side 95 flues are effected by a wall surmounted by a

semicircular brick coping only just impinging upon the shell of the respective cylinders at W.

What I claim as my invention is—

- 5 The combination of boiler-tubes A, B, and E, the latter supported by the first two, with flues N, R, T, and U, and expansion-chambers L and R, the said flues and chambers being of successively increased sectional area, substantially as described.

In testimony whereof I have signed my name to this specification in the presence of two subscribing witnesses.

FOUNTAIN LIVET.

Witnesses:
